UNITED STATES PATENT OFFICE.

HUGH DUNN, OF FALKIRK, SCOTLAND.

MACHINE FOR LINING OR MARKING UP BOOK COVERS.

Application filed September 23, 1925, Serial No. 58,214, and in Great Britain August 5, 1925.

This invention relates to machines for forming the "blind" or other lines such as gold and ink lines on the rounded back of books of miscellaneous sizes and thicknesses in which all the lines are formed in one operation (herein referred to as lining for convenience).

The object of this invention is to provide a machine which will effect the lining in a better manner than heretofore, in that pressure exerted by the lining tools is manually applied and can therefore be suited to the work.

Other features consist in arranging that the book is held stationary; in providing lining tools in the form of discs and mounting these so that they are non-rotatable when "blind" lines are desired, whereby it is found that a glossy or burnished effect is obtained, and rotatably mounting them when gold or ink lines are desired; and in mounting and operating the tools by a lever frame and providing said lever with a number of handles situated at different distances from the fulcrum so that the effective force applied to move the tools can be varied as required.

A setting gauge is also provided for correctly aligning the book and tools in relation to each other.

Referring to the drawings:

Fig. 1 is a perspective view of a lining machine.

Fig. 2 is a longitudinal sectional elevation.

Fig. 3 is in transverse sectional elevation.

Fig. 4 is an elevation of means for inking the tools.

In the particular construction illustrated which will now be described as an example of a machine according to this invention, the apparatus comprises a rectangular box-like main frame 1, having two clamping members 2-3 adapted to receive and hold the book 4; at least one of which clamping members is movable, preferably under the control of a screw 5 operated from a hand wheel 6 on the exterior of the main frame. A setting gauge 7 is provided, and is disposed between the clamping members adapted to position the book in relation to the tools.

On the top of the frame 1 at one end thereof is fixed two spaced bearings 8 carrying a shaft 9 which serves as a pivot for a flat rectangular guide frame 10. This guide

frame extends from one side of the pivot across the top of the main frame and is free at its other end 11.

Slidably mounted on the guide frame is a carriage 12 having downwardly extending lugs 13 which project into the main frame and carry a spindle 14 on which is mounted a series of discs 15 forming the lining tools. For "blind lines" as in the construction illustrated the spindle and discs are fixed by the grub screws 16 (see Fig. 4) so that they do not rotate, for the purpose already described, but for gold or ink lining work they are arranged that the discs rotate.

The carriage has a pin and slot connection at each side thereof with a lever-like frame, the carriage being preferably provided with projecting pins 17 which engage in slots 18 in the frame. This lever frame consists of two bars 19 one at each side of the main frame pivotally mounted at 20. These bars extend upwardly and are provided with a number of transverse rods 21, 22, 23 disposed at different distances from the fulcrum and constituting handles any one of which can be selected by the operator so as to vary the leverage.

The carriage with the lining tools is so arranged that it is rocked on the guide frame and thereby moved from one side to the other of the clamping members under the action of the lever frame. When the tools are idle, such as when a book is being placed into the clamping members, preparatory to lining, the tools will lie at one side of the clamping members. In a position, therefore, directly beneath this idle position of the discs a series of gas burners 25 or other suitable heating devices are disposed so as to heat the tool; it being understood that in the case of gold and ink lining this burner is replaced by appropriate means for applying the ink or gold thereto.

In order to regulate the pressure of the lining tools as they move over the book, the free end 11 of the guide frame can be pressed down to the required extent; this end being normally supported by a transverse frame member 26, which is cut away at 27 on one side so that it can be conveniently grasped by the operator to enable him thereby to press down the guide frame.

Where ink lining is to be performed a device such as shown in Fig. 4 will be provided for inking the discs automatically and such device may comprise an inking roller

30 mounted by the slides 31 in the slot 32 of the bracket 33 and arranged with a spring 34 adapted to press the inking roller downwardly to bear upon the periphery of the discs. An ink container 35 is provided having a roller 36 therein and an intermediate roller 37 adapted to receive ink from the roller in the container and supply it to the inking roller. This inking device 10 is carried by a bracket 38 so as to move with the discs.

This apparatus is simple and cheap to produce and is advantageous in that the book is held quite rigid and the pressure 15 on the tools can be adjusted to any desired extent, giving an even lining.

Having now fully described my invention what I claim and desire to secure by Letters Patent is:-

20 1. A machine for the purpose specified comprising in combination, means for holding the book, lining tools, means for reciprocating the lining tools, and means pivotally mounted at one end and extending 25 across the machine above said book holding means and being manually operable at its free end for moving the lining tools towards the book during reciprocation of the said tools so that the pressure exerted on the 30 lining tools can be suited to the work.

2. A machine for the purpose specified comprising in combination, stationary means for holding the book, lining tools mounted to reciprocate above said book holding means 35 from a position on one side to a position at the other side thereof, and a stationary heating device disposed at one side of the book holding means in a position beneath the lining tools when these are in their ter-

40 minal position at the corresponding side of the book holding means so arranged that the tools are heated while they are idle and are maintained in a heated condition ready for immediate use.

3. A machine for the purpose specified 45 comprising in combination, a clamp for receiving and holding the book in a fixed position, lining tools, a manually operable frame pivoted at one side of the machine, extending across the machine above said 50 clamp, and movable towards or away therefrom so that the pressure of the lining tools can be suited to the work, means for reciprocably mounting said lining tools on said frame and means for moving said tools 55 on said frame.

4. A machine for the purpose specified comprising in combination, a clamp for receiving and holding the book in a fixed position, lining tools, a manually operable 60 frame pivoted at one side of the machine, extending across the machine above said clamp, and movable towards or away therefrom so that the pressure of the lining tools can be suited to the work, means for reciprocably mounting said lining tools on 65 said frame, a manually operable lever-like member pivoted at its lower end to the machine and extending upwardly, means operably connecting said levers to said means for 70 mounting the tools and a number of handles disposed in spaced positions on the upper part of said lever-like members any one of which can be selected so as to vary the 75 leverage of the said member.

In testimony whereof I affix my signature.

HUGH DUNN.
